UNITED STATES PATENT OFFICE.

ALBERT A. GORDON, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

CUTTING AND CLAMPING MECHANISM FOR PICKS AND PICK LOOMS.

Application filed August 6, 1926. Serial No. 127,697.

This invention relates to mechanism for cutting and clamping the weft thread after a fresh weft carrier has been inserted in a pick and pick loom.

In such looms, a plurality of shuttle boxes are provided at the magazine end of the loom, and any shuttle may be moved out of action on any pick of the loom. In such a loom, it frequently happens that a shuttle 10 is thus moved out of running position immediately after the transfer of a fresh carrier thereto and before the weft is threaded in the shuttle eye.

It is necessary that the weft be held in suitable alignment with the shuttle and shuttle eye until the shuttle again goes into action and is picked to the opposite side of the loom.

It is the general object of my invention 20 to provide improved means for cutting the thread between the shuttle and the end holder of the magazine and for clamping and holding the severed thread in position for threading into the shuttle eye.

A further object is to provide a device effective to present the thread in position for cutting and clamping, said device in the preferred form acting also to open the cutting and clamping member so that the thread 30 may be received therein.

My invention further relates to arrangements and combinations of parts which will be hereinafter described and more particularly pointed out in the appended claims.

A preferred form of the invention is shown in the drawings in which

Fig. 1 is a left hand side elevation of certain parts of a pick and pick loom embodying my invention;

Fig. 2 is a plan view of the parts shown in Fig. 1;

Fig. 3 is a similar view but showing certain parts in a different position;

Fig. 4 is a sectional side elevation taken substantially along the line 4-4 in Fig. 3 but with certain parts in a different position;

Fig. 5 is a plan view of parts of a shuttle

box, looking in the direction of the arrow 5 in Fig. 4;

Fig. 6 is a detail sectional view, taken along the line 6-6 in Fig. 5;

Fig. 7 is an enlarged left hand side elevation of a shuttle box, looking in the direction of the arrow 7 in Fig. 3, and

Fig. 8 is a diagrammatic view showing the relation of certain parts of the invention.

Referring to the drawings I have shown a portion of a loom frame 10 having a magazine 11 mounted thereon. A lay 12 is mounted for oscillating movement in the usual manner and supports a plurality of rotary shuttle boxes 13 at the magazine end thereof.

These boxes are mounted upon a sleeve 14 rotatable on a shaft 15 forming an extension of the lay, said sleeve being provided with a gear 16 at one end thereof adapted to be engaged by one or the other of the racks 17 (Fig. 1) secured to the upper end 70 of a box shifting rod 18 which is moved vertically by suitable operating mechanism not shown.

The racks are positioned laterally by rolls 20 (Fig. 1) on a cross bar 21 slidable in a casing 22 and movable laterally by a pin 23 secured to the upper end of an actuating member 24 and positioned in a slot 25 in a cross bar 21. The member 24 is also moved vertically by pattern controlled actuating mechanism not shown.

The different weft carriers are supported in vertical compartments of the magazine, from which they are singly released in the usual manner upon indication of weft exhaustion. The weft carrier thus released drops into a bobbin holder 27 by which it is moved rearward under the transferer 28 which is vertically slidable in a frame 29 carried by the lay 12 and which is actuated by a transfer lever 30.

The parts thus far described are substantially similar to those shown and described in my prior application, Serial No. 92,037, filed March 3, 1926, and these parts in themselves form no separate part of my present

invention, which relates particularly to means for presenting the thread of a freshly inserted weft carrier in position for cutting and clamping between the shuttle eye and the end holder.

Thread cutting and clamping mechanism.

Each rotary shuttle box is provided with an aligned thread cutting and thread clamping device 35 (Figs. 4 to 6) which includes a cutting blade 36 (Fig. 6) and a clamping lug or projection 37. The blade 36 cooperates with a second blade 38 fixed on the frame of the box 13 and the clamping projection 37 fits into a recess 39 in which the end of the thread is clamped after being cut by the blades 36 and 38. The cutting and clamping member 35 is pivoted at 40 at the upper rear corner of the box and a coil spring 41 tends to yieldingly close the cutter, giving the cutting and clamping action. Means for opening the cutter and receiving the thread will be hereinafter described.

It will be noted that each separate shuttle box is provided with an individual thread cutting and clamping device which is at all times movable with the box and operative to hold the thread in any position of the box.

Thread holder and thread positioning device.

The thread holder is mounted in fixed relation to the loom frame 10 and magazine 11 and comprises a clamp or holding device 45 and a casing 46 having a series of vertical openings 47 therein, in which hooked weights 48 are slidably mounted. In threading up the magazine, each weft end is led from a slot at the end of the magazine rearwardly around a projecting arm 50 (Figs. 1 and 3) and is then passed under one of the hooks on the weights 48 and around the clamping device 45.

The thread positioning arm 55 is pivoted at 56 on the casing 46 and is provided with an arm 57 to which a spring 58 is connected for swinging the arm yieldingly to the position indicated in Fig. 2. The arm 55 is provided with an upwardly inclined end portion 60 and with upper and lower thread guiding projections 61 and 62 (Fig. 4). An actuating rod 65 projects laterally from the bobbin holder 27 and is provided with a hook shaped engaging portion 66 at its outer end.

As the holder 27 is moved rearward with a weft carrier W, the thread positioning member 55 is engaged by the actuating rod 65 and by its hook shaped end 66, and is swung about its pivot on the casing 46 from the position shown in Fig. 2 to the position shown in Fig. 3. The weft thread T is thus carried rearward to approximately the position shown in Fig. 3, during which time the active shuttle box 13 is being moved forward to transfer position.

As the lay approaches its forward limit of movement, the upwardly inclined end 60 of the thread positioning arm engages a diamond shaped projection 68 of the cutter 35, raising the combined cutter and clamping member as indicated in Fig. 4, and presenting the weft thread under said member. As the lay completes its forward movement, the portion 60 of the positioning arm 55 passes rearward beyond the projection 68, thus permitting the cutting and clamping member to close, severing the thread, and clamping the severed thread as indicated in Fig. 6.

As the lay thereafter moves rearward the inclined portion 60 of the thread positioning member 65 passes above the projection 68, allowing the clamp to remain closed and hold the weft thread as long as may be desired and until the shuttle is picked from the box, causing the thread to enter the shuttle eye. As the shuttle holder 27 returns to its forward position, the spring 58 swings the arm 55 to the normal position shown in Fig. 2, in which position it is ready to operate in the next succeeding transfer.

One of the purposes of the weights 48 is to yield upwardly as arm 55 places the thread to prevent breakage of the latter. In Fig. 8 there is shown diagrammatically the relation of the stack of bobbins in the magazine, the bobbin holder 27 and the yielding weights 48. When the bobbins U are in the magazine, the ends T extend downwardly toward the arm 50 and thence to one of the weights. All of the ends T of any one stack pass under the hooked part of the corresponding weight and when the lowest bobbin passes downwardly onto the holder 27 the weight will receive a slight downward motion to take up the slack in the threads T.

The relation of the weights and bobbin holder is such that the end T of the bobbin in the holder will be the one which actually supports the weight. It is found as the arm 55 swings to the position shown in Fig. 3, that the end T of the bobbin in the holder is required to move through a lengthened path such as would break the end were it not for the fact that the corresponding weight 48 can rise to permit the increased length of the end required by the swinging of arm 55. It is found even with the first transfer after the magazine has been filled that there will be sufficient yielding of the weight to compensate for the swinging of arm 55 because of the fact that the end T of the bobbin in the holder is nearer horizontal than it was when occupying the lowest position in the stack of bobbins above the holder 27.

Having thus described my invention and the advantages thereof, I do not wish to be limited to the details herein disclosed otherwise than as set forth in the claims, but what I claim is:—

1. In a loom, a weft carrier magazine, a weft end holder, a lay, a plurality of shuttle boxes mounted thereon at the magazine end of the loom, means to move said shuttle boxes to and from active position, means to transfer a weft carrier to the active shuttle box, a thread cutting and clamping device mounted on each shuttle box, and means to actuate the cutting and clamping device associated with the active shuttle box only.

2. In a loom, a weft carrier magazine, a weft end holder, a lay, a plurality of shuttle boxes mounted thereon at the magazine end of the loom, means to move said shuttle boxes to and from active position, means to transfer a weft carrier to the active shuttle box, a thread cutting and clamping device mounted on each shuttle box and engaging the weft between the shuttle eye and the weft end holder, and means to actuate each cutting and clamping device only when its shuttle box is in running position.

3. In a loom, a weft carrier magazine, a weft end holder, a lay, a plurality of shuttle boxes mounted thereon at the magazine end of the loom, means to move said shuttle boxes to and from active position, means to transfer a weft carrier to the active shuttle box, a thread cutting and clamping device mounted on each shuttle box, and a single actuating means for all of said thread cutting and clamping devices, said actuating means being operative only with respect to the cutting and clamping device associated with the actively positioned shuttle box.

4. In a loom, a weft carrier magazine, a weft end holder, a lay, a plurality of shuttle boxes mounted thereon at the magazine end of the loom, means to move said shuttle boxes to and from active position, means to transfer a weft carrier to the active shuttle box, a thread cutting and clamping device mounted on each shuttle box, and means to present thereto the weft thread to be severed as the lay approaches front center.

5. In a loom, a weft carrier magazine, a weft end holder, a lay, a plurality of shuttle boxes mounted thereon at the magazine end of the loom, means to move said shuttle boxes to and from active position, means to transfer a weft carrier to the active shuttle box, a thread cutting and clamping device mounted on each shuttle box, and means mounted at the front of the loom and movable rearward to present the weft thread of the transferred weft carrier in position to be clamped and severed as the lay approaches front center.

6. In a loom, a weft carrier magazine, a weft end holder, a lay, a plurality of shuttle boxes mounted thereon at the magazine end of the loom, means to move said shuttle boxes to and from active position, means to transfer a weft carrier to the active shuttle box, a thread cutting and clamping device

mounted on each shuttle box, and a thread positioning member mounted at the front of the loom and movable rearward as the lay moves forward, said positioning member engaging the weft thread between the end holder and the shuttle and forcing the thread rearward to meet the shuttle advancing with the lay.

7. The combination in a pick and pick loom as set forth in claim 6, in which said thread positioning member also guides the thread up or down to a position to be severed and clamped by the thread cutting and clamping device positioned on the active shuttle box.

8. The combination in a pick and pick loom as set forth in claim 6, in which said thread positioning member when in rearward position is effective to open the thread cutting and clamping device on the active shuttle box as the lay moves forward.

9. The combination in a pick and pick loom as set forth in claim 6, in which said thread positioning member when in rearward position is effective to open the thread cutting and clamping device on the active shuttle box as the lay moves forward, but permits the device to remain closed and grip the thread during rearward movement of the lay.

10. In a loom, a weft carrier magazine, a weft end holder, a lay, a plurality of shuttle boxes mounted thereon at the magazine end of the loom, means to move said shuttle boxes to and from active position, means to transfer a weft carrier to the active shuttle box, a thread cutting and clamping device mounted on each shuttle box, a swinging arm mounted on a fixed pivot at the front of the loom, and means to swing said arm rearward as the thread carrier is presented in position, said arm positioning said weft thread as it moves rearward and being operative when in rearward position to engage and open said thread cutting and clamping device.

11. In a loom, a weft carrier magazine, a weft end holder, a lay, a plurality of shuttle boxes mounted thereon at the magazine end of the loom, means to move said shuttle boxes to and from active position, means to transfer a weft carrier to the active shuttle box, a thread cutting and clamping device mounted on each shuttle box, a swinging arm mounted on a fixed pivot on the front of the loom, a bobbin holder movable rearwardly to present said weft carrier in transfer position, and an actuating member projecting laterally from said bobbin holder and engaging said arm to swing said arm rearwardly as the bobbin holder moves rearward, said arm when thus swung rearward engaging and positioning the weft thread, and engaging and opening the thread cutting and clamping device when in rearward position.

12. In a weft replenishing loom, a weft

4
carrier magazine, a lay, shifting shuttle boxes on the end of the lay adjacent the magazine, thread cutting mechanism, a thread holding device to hold the ends of the threads extending from the weft carriers in the magazine, means to receive a weft carrier from the magazine and move the same to transfer position, a thread placing member operable by said receiving means to present

the thread of the weft carrier thereon to the 10 cutting mechanism, and a yieldable slack taking-up element to vary the length of the thread from the holding device to said weft carrier.

5 In testimony whereof I have hereunto af- 15 fixed my signature.

ALBERT A. GORDON.
